UNITED STATES PATENT OFFICE.

JOSEPH J. HEINDL, OF BROOKLYN, NEW YORK.

STEAM-ENGINE VALVE-GEAR.

SPECIFICATION forming part of Letters Patent No. 399,531, dated March 12, 1889.

Application filed December 26, 1888. Serial No. 294,592. (No model.)

To all whom it may concern:

Be it known that I, JOSEPH J. HEINDL, of Brooklyn, Kings county, and State of New York, have invented certain new and useful 5 Improvements in Steam-Engine Valve-Gears, of which the following is a specification, reference being had to the accompanying drawings.

My invention relates specially to the construction, arrangement, and adaptation of a valve-gear for three-cylinder engines, whereby they may be operated without the use of eccentrics, and whereby an economical admission, distribution, and expansion of the steam 15 may be effected while passing through the cylinders to accomplish its work.

My improvements are specially adaptable to three-cylinder or triplex pumps as a means for operating the three pumps at once and for 20 effecting a higher movement of piston and rate of revolution. The special features of this improved gear consist in having a series 25 of main-valve-operating levers attached directly at their shorter portions or ends to the several pistons and their longer ends to a 30 vibrating fulcrum acting also as a support for said longer ends. To a bearing-pin formed in each of said main-valve-operating levers is attached a connecting-rod operating a triple- 35 crank shaft, the cranks of said crank-shaft being set at angles of one hundred and twenty degrees to each other. Said triple-crank shaft wears in special bearings and carries fly-wheels for effecting regularity of motion. 40 This triple-crank shaft is specially located out or apart from the center line of piston-rods, and in such position that a line drawn through the center of bearing-pin for connecting-rods and through the center of crank- 45 shaft shall not be parallel to the center line of cylinder and rods to prevent the possibility of any two of the pistons or valves coming abreast of each other. The center lines of motion not being parallel to each other, the 50 movements of cranks and pistons are not in exact unison, the cranks, for instance, having a portion of their upward or downward movement still in progress when their associate pistons have passed to a reverse movement.

Referring to the drawings, Figure 1 represents a cross-section through one of the three cylinders, also a general mid-position arrange-

ment of the valve-operating mechanism. Fig. 2 represents a longitudinal elevation of a three-cylinder engine with sectional portions 55 of valve-gear details of the first and second cylinders and an outside elevation of the third cylinder. Fig. 3 represents a plan view of the three cylinders with the immediate 60 valve-stem connections shown in section and in detail. Figs. 4 and 5 represent details of the main valve-operating lever, that in Fig. 4 having the secondary lever attached and in place, as used for operating the valves under ordinary practice, that in Fig. 5 being without such secondary lever, as used when steam is admitted beneath the valve, as through the exhaust-port instead of being admitted from the chest, as in ordinary practice. Figs. 6, 7, 65 and 8 are details of slide-valves in varied positions, that in Fig. 8 showing exhaust-port admission.

Similar letters of reference designate like parts or portions in all the figures.

The letter A designates the engine-cylinders and identified in Figs. 2 and 3 by the letters A' A² A³.

B designates the piston, Fig. 1, and C the piston-rods, the rods being identified by C' C² C³. c designates the piston-rod bosses, to which 80 the main-valve-operating levers D are attached. These levers are identified by D', D², and D³, according to the cylinder to which they belong. The shorter portions of these levers D are attached to the bosses c of the 85 piston-rods, while the longer portions are attached to and center on a vibrating fulcrum-support, E, attached to and swinging upon a fixed center, F.

To a lever-pin or bearing, G, forming a part 90 of the main-valve-operating levers D, is attached a connecting-rod, H, for the purpose of operating a triple-crank shaft, I, each crank controlling and being operated from the piston-rod of each of the cylinders. To this same 95 lever-pin or bearing G is also attached a secondary lever, K, swinging upon and supported by a suspension-rod, L, as a fulcrum. Attached to the shorter portion of lever K is the suspension and connecting rod N, communicating the motion of secondary lever K to valve-lever O. M and Q are fixed brackets for supporting fulcrum-rods L and P. There are three fulcrum-rods P, one to each 100

cylinder-valve, and these fulerum-rods P support the valve-operating levers O. Lever O is preferably made with a slot at the valve-stem end, within which slot a bearing, X, for 5 the valve-stem pin moves to and fro for purposes of adjustment as to throw of valve. To the shaft of fulerum-rods P is attached a special lever, R, operated and adjusted by means of a turn-buckle, T, acting to lengthen 10 or shorten rod-connection S, one end of which is fixed to bearing U.

V designates the valve-stems to each valve W.

In Fig. 3, the plan view, it will be noticed 15 that the gear of cylinder A' operates the valve of cylinder A³, gear of cylinder A² that of A', and gear of A³ that of A².

In the general operation of this gear the 20 position of the piston and rod, through the lever-boss c, together with the position of the crank-shaft and connecting-rod, as also of the main-valve-operating lever D, as also, when used, of the secondary-valve-operating lever K, control the position of the several steam- 25 valves, while the adjusting-rod S, lengthened or shortened by the turn-buckle T, together with the attached lever R and fulerum-support P, control the throw of the several valves.

In the sectional view, Fig. 1, the mid or central 30 position of the several parts is shown in detail, while dotted center lines outline and define their extreme and relative positions. Line a designates the extent of movement of piston-rod boss as well as the stroke of the several pistons. b, b', and b² designate the position of boss c and the attached lever at extreme throw or position of pistons, also the mid-position. b², b³, and b⁴ mark the positions of c center for the three crank positions, 35 as shown. d², d³, and d⁴ are corresponding points of position of the lever-pin G. d and d' mark the positions of lever-pin G, corresponding to positions e and e' of cranks. e², e³, and e⁴ of crank positions correspond with 40 d², d³, and d⁴ of lever-pin G positions, and of b², b³, and b⁴ of c center of piston-rod boss. Now lever K, when used, moves at its outer end to h², h³, and h⁴, corresponding to positions d², d³, and d⁴ of lever-pin G center. 45

50 With positions h², h³, and h⁴ lever O moves, through the communication of rod N, to positions f², f³, and f⁴, and the opposite end of lever O, communicating with valve-stem V, moves to positions g², g³, and g⁴, and the valves have 55 positions k², k³, and k⁴, all these several positions corresponding with positions e², e³, and e⁴ of the several cranks. All these several positions, as well as those between them, are occupied by the several valves, levers, connections, and cranks, according as they move 60 through their travel, and the pistons move up and down or to and fro through the cylinder. Now to vary the throw of the valves, making such throw longer or shorter, as may be required, the turn-buckle or nut T is operated to lengthen or shorten the connection S, the end bearing, U, being fixed, thereby

raising or lowering lever R on an arc, m m, and the vibrating fulerum P on the arc n n to or from the valve-stem V, resulting in the 70 proportionate lengthening or shortening of the throw of the valve. As the vibrating fulerum P moves from the valve-stem, it lengthens the distance between the center P and the center of valve-stem V. The 75 fulerum P is of course only moved to and fro by the adjustment in the length of S, and only when it is required to lengthen or shorten the throw of valve W. As shown by section in Fig. 3, the valve-operating mechanism of each engine operates the valves of some other one of the three engines, and preferably of that engine whose crank follows immediately after its own crank in the circle of revolution. Thus the valve-moving mechanism operated from crank-pin e² moves the valves of the cylinder A³, operating on crank-pin e³, the mechanism operated from crank-pin e³ moves the valves of cylinder operating on crank-pin e⁴, and that from crank e⁴ moves 80 valves of cylinder E², operating on crank e², steam being admitted through the chest by the opening of the outer edges of the main valve and ports, after the well-known and usual manner. Should, however, some of the 85 new forms of valves admitting steam through the exhaust-passage, instead of through the chest, be used, the valve would of course move in an opposite direction to that admitting steam direct from inclosing-chest. Then the secondary lever K would not be necessary and would be omitted, and connection N take direct hold of the main-valve-operating lever D, as shown in Fig. 5, at points or positions h² h³ h⁴ of said valve-operating lever. The 90 valve shown in Fig. 8 has the central steam admission used in connection with the lever of Fig. 5—that is, the steam is admitted to the cylinder through exhaust-passage instead of through the chest, after the manner of some 95 piston-valves now in use. A puppet-valve may of course take the place of the slide-valve W and be moved up and down by the stem V, the principal detail changes being in the 100 shape of valves themselves.

115 What I claim as new, and desire to secure by Letters Patent, is—

1. In a three-cylinder engine, in combination with the piston-rod of any one of the said cylinders, a main-valve-operating lever 120 connected to and operated by said piston-rod and swinging upon a vibrating fulerum, a pitman or connecting-rod joining said main-valve-operating lever with one of the crank-pins of a triple-crank shaft, a secondary lever 125 connected to and operated by said main operating-lever, a vibrating fulerum supporting said secondary lever, a pitman or connection between said secondary lever and a valve-operating lever, and a connecting 130 valve-stem and valve of a second cylinder of the set of three, substantially as set forth.

2. In a three-cylinder engine, in combination with the piston-rod of any of the said

cylinders, a main-valve-operating lever connected to and operated by said piston-rod and swinging upon a vibrating fulcrum, a pitman or connecting-rod joining said main-valve-operating lever with one of the crank-pins of a triple-crank shaft, a secondary lever connected to and operated by said main-valve-operating lever, a vibrating fulcrum supporting said secondary lever, a pitman or connecting-rod joining said secondary lever to a slotted-valve-operating lever, a vibrating fulcrum or support for said slotted-valve-operating lever, and means for adjusting the position of said fulcrum-support, and a valve-stem and valve of a second cylinder of the set of three connected to and operated by said slotted-valve-operating lever, substantially as and for the purposes set forth.

3. A valve-adjusting mechanism for steam-cylinder steam-chests, consisting of a slotted lever attached directly to the valve-stem, a vibrating fulcrum-support for said slotted lever made adjustable to or from the valve-stem to lengthen or shorten the throw of valve, an adjusting-arm or lever operating through a rock-shaft, to which both the vibrating fulcrum-support and the adjusting-arm are attached, a fixed bearing for the support of said rock-shaft, and a turn-buckle rod adapted to be lengthened or shortened, one end of said turn-buckle rod being attached to said adjusting-arm and the other to a fixed center or swing support, substantially as set forth.

4. In a three-cylinder engine, in combination with the piston-rod of any one of said cylinders, a main-valve-operating lever connected to and operated by said piston-rod and swinging upon a vibrating fulcrum, a pitman or connecting-rod joining said main-operating-lever with one of the crank-pins of a triple-crank shaft, a rod connecting said main-valve-

operating lever directly with the valve-lever, the valve-lever operating upon a vibrating support, and the connected valve and valve-stem of a second cylinder of the set of three, substantially as set forth.

5. In a three-cylinder engine, in combination with the piston-rod of any one of said cylinders, a main-valve-operating lever attached to and operated by said piston-rod and swinging upon a vibrating fulcrum, a pitman or connecting-rod joining said main-valve-operating lever with one of the crank-pins of a triple-crank shaft, a connecting-rod directly attached to and operated by said main operating-lever and communicating motion to and operating a slotted-valve lever, a vibrating fulcrum-support for said slotted-valve lever, and means or mechanism for adjusting the position of said fulcrum or support to effect a longer or shorter throw of valve, and a valve-stem and valve of a second cylinder of the set of three connected to and operated by said slotted lever, substantially as and for the purposes set forth.

6. In a three-cylinder-engine, the combination of the piston-rods of said engine, main-valve-operating levers connected directly to said piston-rods and swinging upon a vibrating fulcrum, connecting-rods joining said levers to the cranks of a triple-crank shaft, said crank-shaft being placed in such position that the center line of motion of said connecting-rods shall not be parallel with the center line of motion of the said piston-rods, whereby the movements of the cranks, valves, and piston-rods are never in exact unison with each other, substantially as set forth.

JOSEPII J. HEINDL.
